(57) **CLAIM**

The ornamental design for a ring charging case, as shown and described.

DESCRIPTION

FIG. 1 is a perspective view of the ring charging case in a closed state in accordance with the present design;

FIG. 2 is a perspective view of the ring charging case thereof in an open state;

FIG. 3 is a top view of the ring charging case thereof in a closed state;

FIG. 4 is a front-on side view of the ring charging case thereof in a closed state;

FIG. 5 is a left side view of the ring charging case thereof in a closed state;

FIG. 6 is a right side view of the ring charging case thereof in a closed state;

FIG. 7 is a bottom view of the ring charging case thereof in a closed state;

FIG. 8 is a top view of the ring charging case thereof in an open state;

FIG. 9 is a front-on side view of the ring charging case thereof in an open state;

FIG. 10 is a left side view of the ring charging case thereof in an open state;

FIG. 11 is a right side view of the ring charging case thereof in an open state;

FIG. 12 is a bottom view of the ring charging case thereof in an open state; and,

FIG. 13 is a perspective view of the ring charging thereof in an open state, where a ring is received in the ring charging case.

The broken lines on the ring charging case depict portions of the ring charging case that form no part of the claimed design. In FIG. 13, the broken lines depicting a ring are environmental subject matter and form no part of the claimed design.

1 Claim, 11 Drawing Sheets
